EDGE TOOL

Ruby Anne Jarveaux Wilson, New Orleans, La.;
 Margaret Wilson Johnson, administratrix of
 said Ruby Anne Jarveaux Wilson, deceased

Application January 9, 1946, Serial No. 639,958

2 Claims. (Cl. 30—349)

1

My invention relates to improvements in edge tools, especially knives and the like.

The primary object of the invention is to inexpensively equip a cutting blade with a removable and replaceable, rigid, bevel-edge cutting member interlocking with the blade to provide rigidity, and which may be formed of a different material than the blade better adapted to retain its edge, and is adapted for resharpening so as to constitute a replacement part.

Other and subordinate objects also comprehended by my invention, together with the precise nature of my improvements, and the manifold advantages thereof, will be readily understood when the succeeding description and claims are read with reference to the drawing accompanying and forming part of this specification.

In said drawing—

Figure 1 is a view in perspective illustrating my invention in a preferred embodiment thereof,

Figure 2 is a view in end elevation drawn to an enlarged scale,

Figure 3 is a fragmentary view in perspective of a modified embodiment of the cutting member,

Figure 4 is a view in end elevation of another modified embodiment of the cutting member, and

Figure 5 is a view in side elevation of still another modified embodiment of the invention.

Referring to the drawing by numerals, and first to Figures 1 and 2, my invention has been shown therein by way of exemplification, as comprising a knife, or other tool, blade 1 forming a holder for a bevel cutting edge member 2. The knife blade 1 is of bevel form with sides 3 converging to a blunt leading edge 4.

The cutting edge member 2 is likewise of bevel form, coextensive in length, substantially, with said blade 1 and narrower than said blade, and is provided with an outer cutting edge portion 5 bevelled in conformity with the angle of convergence of the sides 3 of said blade 1 and which has a root thickness corresponding to the thickness of said blunt edge 4 for a purpose presently seen. At its opposite edge 6 the cutting edge member 2 is flat, and between said edges 5, 6 is provided with sides 7 which converge to the root of the cutting edge portion 5 at a lesser angle than the sides 3 of said blade 1. The sides 7 are provided with longitudinally extending flutes, or ribs, 8, preferably of square form in cross-section.

A longitudinal recess 9 is provided in the knife blade 1 in the median plane thereof and extending from end to end of the blade, said recess extending into said blade from the leading edge 4.

2

a depth corresponding to the width of the sides 7 of said member 2 between the root of the cutting edge portion 5 and the edge 6 of said member. The sides of the recess 9 are provided with longitudinal flutes, or ribs, 10 adapted to interfit with the flutes, or ribs, 8 of said member 2, and the member 2 is slidably fitted in said recess 9 for removal endwise but is interlocked therein against removal laterally by the interfitting flutes, or ribs, 8, 10.

Fasteners may be provided at each end of the cutting blade 1 for preventing endwise creeping of the cutting edge member 2 in the recess 9. As shown in Figure 2, said fasteners may take the form of flat, metal fingers, as at 11, countersunk in the end of the blade 1 and secured to said end by screws 12 with one end portion overlapping the corresponding end of said member 2 and provided with a nub 13 bearing against said end of said member.

As shown in Figure 3, the cutting edge portion 14 of the cutting edge member 15 may be saw-toothed. Otherwise, said member 15 is identical with the described member 2.

As will now be seen, my invention provides a cutting edge member in a bevel-sided holder, which may be a knife or other tool blade, said member having a cutting edge portion the sides of which are coplanar with the bevel sides of the holder, and which portion extends out of the holder. The cutting edge member is removable easily for replacement, when dull, by a new one, or for sharpening and subsequent replacement, and may be formed of a harder material than that of the holder adapting the same to hold a cutting edge.

In the modified embodiment of my invention shown in Figure 4, the cutting edge member 16 has the form of a half section of the member 2 longitudinally split therefrom so that the member 16 is formed with a cutting edge portion bevelled on one side only and designated 17, and with flutes, or ribs, 18 on the corresponding side of the member only. As will be understood, this modified cutting edge member is designed to be fitted in a blade, not shown, having a correspondingly shaped and constructed recess therein.

In the modified embodiment of the invention shown in Figure 5, a cutting edge member 19, similar to the member 2, is provided in one blade 20 of a pair of shears 21, in the same manner as in the first described embodiment of the invention, with the following exceptions. A side fastener lug 22 on the member 19 is secured by a screw 23 to said member to fit in an aperture 24.

in the blade 20 for preventing endwise creeping of said member 19.

The foregoing will, it is believed, suffice to impart a clear understanding of my invention without further explanation.

Manifestly, the invention, as described, is susceptible of modification without departing from the inventive concept, and right is herein reserved to such modifications as fall within the scope of the appended claims.

What I claim is:

1. A blade-like holder of elongated form and triangular shape in cross-section with sides converging to a blunt edge and having a longitudinal recess extending therein from said blunt edge, and a cutting edge member set into said recess and having a bevelled cutting edge portion extending out of said recess provided with sides coplanar with the sides of said holder, said recess and said member having interfitting fluted sides for preventing the member from displacement out of said recess in the direction of said edge, said interfitting sides converging from the bottom of said recess to said blunt edge at a lesser angle than the sides of said holder and the sides of 25 said bevelled cutting edge portion.

2. A blade-like holder of elongated form and triangular shape in cross-section with sides converging to a blunt edge and having a longitudinal recess extending therein from said blunt edge, and a cutting edge member set into said recess and having a bevelled cutting edge portion extending out of said recess provided with sides coplanar with the sides of said holder, and means on the holder confining said member in said recess against movement along the same comprising flat fingers countersunk in the ends of said holder and cutting edge member and detachably secured to said ends of said holder.

RUBY ANNE JARVEAUX WILSON.
